UNITED STATES PATENT OFFICE

2,209,465

PHYSICAL CULTURE AND EXERCISING
DEVICE

Anthony Matysek, Baltimore, Md.

Application July 15, 1938, Serial No. 219,434

1 Claim. (Cl. 128—57)

This invention relates to improvements in physical culture and exercising devices, and has for its object to provide a device of this character in which the weight can be increased or decreased 5 as desired.

A further object of the invention is to provide the device with a cylinder adapted to revolve and in which the weight can be increased or decreased as desired, said cylinder being used for 10 rolling over the abdomen, when the user is in an inclining position, for the purpose of reducing the abdomen.

The invention consists of the novel construction and arrangement of the parts and combination 15 of parts hereinafter more fully set forth in the following specification and pointed out in detail in the appended claim.

In the accompanying drawing:

Figure 1 is an elevation of my invention.

20 Figure 2 is a vertical longitudinal section of Figure 1.

Figure 3 is an end view of Figure 1.

Referring to the accompanying drawing, forming 25 part of this specification, and in which like reference numerals designate like parts throughout the several views thereof, 1 designates a cylinder having an aperture 2 in each end thereof and is revolvably mounted on a rod 3. The said cylinder is closed at each end when on the rod 3 and forms a chamber surrounding said rod in which shot or other weights can be placed to increase the weight of the device. Also mounted 30 on the rod 3 adjacent the said cylinder 1 are washers 4. Also mounted on the rod 3 are a number of weights 5, 6 and 7 near each end of the said rod 3 and adjacent the weights 5 are washers 8, also mounted on the rod 3. Revolvably mounted on the said rod 3, between the washers 4 and 8, are sleeves 9 which form hand-holds for

the device when being used. The rod 3 is provided at each end with a collar 10 to hold the parts in position thereon, said collars being held to the rod by the thumb-screws 11. The weight of the device can be varied by reducing or adding to the number of weights 5, 6 and 7. The cylinder 1 can also be filled with shot, or pieces of metal, 12 to increase the weight of the device. When it is desired to remove the shot 12 to reduce the weight of the device, or to add more shot to increase the weight, one of the collars 10 can be loosened and removed from the rod 3 and the latter pulled back into the cylinder 1, leaving one of the apertures 2 open for the purpose of removing some, or all, of the shot 12 from, or adding more to, the cylinder. When the device is used for reducing the abdomen, the user will lie upon his back and by grasping the device by the sleeves 9, the cylinder 1 can be rolled back and forth over the abdomen, and when being used as an exercising device, it can be simply lifted and lowered or used in any other manner desired.

Having thus described my invention, what I claim is:

A physical culture and exercising device, comprising a rod, a cylinder revolvably mounted at its ends on said rod and having a chamber therein adapted to hold weights, weights revolvably mounted on said rod near each end thereof, sleeves loosely mounted on said rod between the ends of said cylinder and said weights, washers mounted on said rod adjacent each of said sleeves, a collar adjustably mounted on each end of said rod to hold the parts in position thereon, and a set screw in each of said collars to hold them in the adjusted position on said rod.

ANTHONY MATYSEK.
